UNITED STATES PATENT OFFICE.

JESSE E. O'NEEL AND EUGENE JENKINS, OF TILLAMOOK, OREGON.

TONE-MODULATOR FOR GRAPHOPHONES.

No. 905,220.

Specification of Letters Patent.

Patented Dec. 1, 1908.

Application filed May 29, 1908. Serial No. 435,774.

To all whom it may concern:

Be it known that we, JESSE E. O'NEEL and EUGENE JENKINS, citizens of the United States, residing at Tillamook, in the county 5 of Tillamook, State of Oregon, have invented certain new and useful Improvements in Tone - Modulators for Graphophones; and we do hereby declare the following to be a full, clear, and exact description of the invention, such as will enable others skilled in 10 the art to which it appertains to make and use the same.

The present invention relates to improvements in tone - modulating devices for 15 graphophones, and it resides, generally, in the provision of an extremely simple, inexpensive, and efficient device adapted for attachment to a sound-box of any ordinary type and including a pair of oppositely-disposed jaws movable into and out of engagement with the vibrating transmitter-bar of 20 the sound-box, so as to control the amplitude of the vibrations.

The preferred embodiment of the invention is illustrated in the accompanying drawings, in which corresponding parts are designated by the same reference numerals throughout the several views.

Of the said drawings, Figure 1 is a front 30 elevation of the sound-box of a graphophone with the improved modulator attached thereto, a portion of the tongue of the clamp being broken away. Fig. 2 is a rear elevation of the modulator. Fig. 3 is a section 35 taken vertically through the modulator.

Referring more particularly to the drawings, 1 designates a sound-box of any ordinary construction, 2 the mica diaphragm thereof, 3 the needle holder, and 4 the vibratory transmitter bar which is connected at its lower end with said holder and at its upper end with the diaphragm in the usual manner.

The modulator which is designed for use 45 in connection with the sound box comprises a supporting strap 5 provided at each end with a lateral flange 6 having a central perforation formed therein through which an adjusting screw 7 extends, the inner end of 50 each screw impinging against an arcuate lateral flange formed upon the outer edge of a slide 8, said slides being movable upon the ends of the strap with which they are engaged by means of pairs of ears 9 which

extend across the upper and lower edges of 55 the strap and are bent towards each other as shown, the movement of the slides in one direction being limited by the contact of their upper ears with the shoulders 10 resultant from the formation of the V-shaped 60 bend 11 intermediate the ends of the strap. The supporting strap further includes an integral tongue 12 which forms an extension of the bend 11 and has its major portion arranged in spaced relation to and parallel 65 with the front face of the strap. In the space between the tongue and the strap is fitted a pair of oppositely-disposed jaws 13 pivoted intermediate their ends as indicated by the numerals 14, 14, the pivot pins passing through the tongue and through the strap. Towards their lower ends, the jaws are connected by means of a pin 15 whose opposite ends fit in alining sockets formed in the inner or mutually-adjacent edges of the 75 jaw, said pin being embraced by a tiny expansible coil spring 16, the tension of which normally forces the lower ends of the jaws away from each other.

The lower ends of the jaws are forced 80 towards each other against the action of the spring by means of an endwise movable threaded rod 17 which extends through an opening formed in the laterally-bent upper end of the tongue and has its tapered or 85 wedge-shaped lower end fitted between the upper ends of said jaws. The upper end of said rod is provided with a milled head 18, by means of which it is rotated, the inward movement of said rod effected by its rotation 90 in one direction causing its lower end to advance between the upper ends of the jaws, forcing said ends away from each other, in consequence of which the lower ends of the 95 jaws will approach each other.

In attaching the device to the sound-box, the slides 8 are tightened against the side wall thereof, by means of the screws 7, the laterally-bent upper end of the transmitter-bar passing between the inner edges of the 100 jaws which as above stated, are normally forced away from each other by the coil-spring 16. When it is desired to modulate the sound vibrations, the rod 17 is moved inwardly, whereupon the lower ends of the 105 jaws will be forced into contact with the transmitter bar at opposite sides thereof, the inward movement of said rod being con-

tinued, until the requisite pressure is exerted upon said bar, the tone softening as the tension upon the bar increases.

The strap and the slides are preferably constructed of brass and the jaws of aluminum, the latter metal imparting a peculiarly soft tone to the instrument upon which it is placed and permitting a more gradual modulation of the tone.

10 If preferred, each jaw may have secured to the lower edge thereof a thin facing or cushion of rubber 20.

It will be apparent from the foregoing, that the tone regulation is at all times under 15 the control of the operator, the changes in tone being effected merely by a rotation of the controlling rod 17 in one direction or the other, without necessitating the stopping of the instrument. It will likewise be apparent that by reason of the simplicity of 20 the device, it may be constructed at an extremely low cost.

What is claimed is:

1. The combination, with the sound box 25 of a graphophone, and its transmitter-bar, of a tone-modulator, comprising a support adapted for attachment to the sound-box, and a pair of oppositely-disposed members carried by the support and movable into and 30 out of engagement with the transmitter-bar.

2. The combination, with the sound box 35 of a graphophone, and its transmitter-bar, of a tone-modulator, comprising a support adapted for attachment to the sound-box, and a pair of oppositely-disposed members carried by the support and movable simultaneously into and out of engagement with the 40 transmitter-bar.

3. The combination, with the sound box 45 of a graphophone, and its transmitter-bar, of a tone-modulator, comprising a support adapted for attachment to the sound-box, and a pair of oppositely-disposed jaws pivoted to the support and movable into and out of engagement with the transmitter-bar.

4. The combination, with the sound box 50 of a graphophone, and its transmitter-bar, of a tone-modulator, comprising a support adapted for attachment to the sound-box, and a pair of oppositely-disposed jaws pivoted to the support and movable simultaneously into and out of engagement with the transmitter-bar.

5. The combination, with the sound box 55 of a graphophone, and its transmitter-bar, of a tone-modulator, comprising a support adapted for attachment to the sound-box, and a pair of transversely-disposed members carried by the support and arranged upon 60 opposite sides of the transmitter-bar, said members being movable into and out of engagement with said bar.

6. The combination, with the sound box 65 of a graphophone, and its transmitter-bar, of a tone-modulator, comprising a support adapt-

ed for attachment to the sound-box, and a pair of transversely-disposed members pivoted to the support and arranged upon opposite sides of the transmitter-bar, said members being movable into and out of engagement with said bar. 70

7. The combination, with the sound box of a graphophone, and its transmitter-bar, of a tone-modulator, comprising a support adapted for attachment to the sound-box, and a 75 pair of transversely-disposed members carried by the support and arranged upon opposite sides of the transmitter-bar, said members being movable simultaneously into and out of engagement with said bar.

8. The combination, with the sound box of a graphophone, and its transmitter-bar, of a tone-modulator, comprising a support adapted for attachment to the sound-box, and devices carried by said support and arranged 80 upon opposite sides of the transmitter-bar, for engagement with said bar. 85

9. The combination, with the sound box of a graphophone, and its transmitter-bar, of a tone-modulator, comprising a support adapted 90 for attachment to the sound-box, a pair of jaws carried by the support and arranged for engagement with the transmitter-bar, and means for adjusting the tension of said jaws upon said bar. 95

10. The combination, with the sound box of a graphophone, and its transmitter-bar, of a tone-modulator, comprising a support adapted for attachment to the sound-box, a pair of jaws pivoted to the support and arranged upon opposite sides of the transmitter-bar, for engagement therewith, and means for adjusting the tension of said jaws upon said bar. 100

11. The combination, with the sound box of a graphophone, and its transmitter-bar, of a tone-modulator, comprising a support adapted for attachment to the sound-box, a pair of jaws pivoted to the support and arranged upon opposite sides of the transmitter-bar, for engagement therewith, and endwise-movable means for adjusting the tension of said jaws upon said bar. 105

12. The combination, with the sound box of a graphophone, and its transmitter-bar, of a tone-modulator, comprising a support adapted for attachment to the sound-box, a pair of jaws pivoted to the support and arranged upon opposite sides of the transmitter-bar, for engagement therewith, and an endwise-movable member carried by said support and engaged with said jaws, for adjusting the tension of said jaws upon said bar. 110

13. The combination, with the sound box of a graphophone, and its transmitter-bar, of a tone-modulator, comprising a support adapted for attachment to the sound-box, a pair of jaws pivoted intermediate their ends to the support and arranged upon opposite 115 120 125 130

- 5 sides of the transmitter-bar, and an endwise-
movable member having one end thereof ex-
tending between the adjacent ends of said
jaws, for forcing the other ends of the latter
into engagement with said bar.
14. The combination, with the sound box
of a graphophone, and its transmitter-bar,
of a tone-modulator, comprising a support
adapted for attachment to the sound-box, a
10 pair of jaws pivoted intermediate their ends
to the support and arranged upon opposite
sides of the transmitter-bar, and an endwise-
movable member having a tapered end ex-
tending between the adjacent ends of said
15 jaws, for forcing the other ends of the latter
into engagement with said bar.
15. The combination, with the sound box
of a graphophone, and its transmitter-bar,
of a tone-modulator, comprising a support
20 adapted for attachment to the sound-box, a
pair of jaws pivoted intermediate their ends
to the support and arranged upon opposite
sides of the transmitter-bar, and an endwise-
movable rotatable member having a tapered
25 end extending between the adjacent ends of
said jaws, for forcing the other ends of the
latter into engagement with said bar.
16. The combination, with the sound box
of a graphophone, and its transmitter-bar,
30 of a tone-modulator, comprising a support
adapted for attachment to the sound-box, a
pair of jaws pivoted intermediate their ends
to the support and arranged upon opposite
sides of the transmitter-bar; means for nor-
35 mally forcing the lower ends of the jaws
away from each other and from the bar; and
means arranged for engagement with the
upper end of said jaws to force said lower
ends towards each other and into engage-
40 ment with said bar, against the action of the
first-mentioned means.
17. The combination, with the sound box
of a graphophone, and its transmitter-bar,
45 of a tone-modulator, comprising a support
adapted for attachment to the sound-box, a
pair of jaws pivoted intermediate their ends
to the support and arranged upon opposite
sides of the transmitter-bar; means for nor-
50 mally forcing the lower ends of the jaws
away from each other and from the bar, and
the upper ends thereof towards each other;
and an endwise-movable member having its
lower end fitting between the upper ends of
55 said jaws, for forcing the same away from
each other and the lower ends thereof to-
wards each other and into engagement with
said bar, against the action of the first-men-
tioned means.
18. The combination, with the sound box
60 of a graphophone, and its transmitter-bar,
of a tone-modulator, comprising a support
adapted for attachment to the sound-box, a
pair of jaws pivoted intermediate their ends
to the support and arranged upon opposite
65 sides of the transmitter-bar; means for
- normally forcing the lower ends of the jaws
away from each other and from the bar, and
the upper ends thereof towards each other;
and an endwise-movable member having a
70 tapered lower end fitting between the upper
ends of said jaws, for forcing the same away
from each other and the lower ends thereof
towards each other and into engagement
75 with said bar, against the action of the first-
mentioned means.
19. The combination, with the sound box
of a graphophone, and its transmitter-bar,
of a tone-modulator, comprising a support
adapted for attachment to the sound-box,
and a pair of oppositely-disposed members
80 carried by the support and movable into
and out of engagement with the transmis-
ter-bar, each member being provided with a
facing of yielding material.
20. The combination, with the sound box
85 of a graphophone, and its transmitter-bar,
of a tone-modulator, comprising a support
adapted for attachment to the sound box,
and a pair of oppositely-disposed members
90 carried by the support and movable into
and out of engagement with the transmis-
ter-bar, each member being provided with a
facing of rubber.
21. The combination, with the sound box
95 of a graphophone, and its transmitter-bar,
of a tone-modulator, comprising a support
adapted for attachment to the sound-box,
and a pair of oppositely-disposed jaws piv-
100 oted to the support and movable into and
out of engagement with the transmitter-bar,
each jaw being provided with a facing of
yielding material.
22. The combination, with the sound box
105 of a graphophone, and its transmitter-bar,
of a tone-modulator, comprising a support
adapted for attachment to the sound-box,
and a pair of oppositely-disposed jaws piv-
110 oted to the support and movable into and
out of engagement with the transmitter-bar,
each jaw being provided with a facing of
rubber.
23. The combination, with the sound box
115 of a graphophone, and its transmitter-bar,
of a tone-modulator, comprising a support
adapted for attachment to the sound-box,
and gripping means carried by the support
and arranged for engagement with the trans-
mitter-bar.
24. The combination, with the sound box
120 of a graphophone, and its transmitter-bar,
of a tone-modulator, comprising a support
adapted for attachment to the sound-box,
gripping means carried by the support and
arranged for engagement with the trans-
mitter-bar; and means for adjusting the ten-
sion of said gripping means upon said bar.
25. The combination, with the sound box
125 of a graphophone, and its transmitter-bar,
of a tone-modulator, comprising a support
adapted for attachment to the sound-box,

and gripping means carried by the support and arranged for engagement with the transmitter-bar, the gripping edges of said means having a facing of yielding material secured 5 thereto.

26. The combination, with the sound box of a graphophone, and its transmitter-bar, of a tone-modulator, comprising a support adapted for attachment to the sound-box, 10 and gripping means carried by the support

and arranged for engagement with the transmitter-bar, the gripping edges of said means having a facing of rubber secured thereto.

In testimony whereof, we affix our signatures in presence of two witnesses.

JESSE E. O'NEEL.
EUGENE JENKINS.
